UNITED STATES PATENT OFFICE.

WILLIAM E. WINE, OF TOLEDO, OHIO.

DOOR ARRANGEMENT FOR RAILWAY CARS.

Application filed January 12, 1922, Serial No. 528,654. Renewed January 21, 1924.

To all whom it may concern:

Be it known that I, WILLIAM E. WINE, a citizen of the United States of America, residing at Toledo, in the county of Lucas and State of Ohio, have invented certain new and useful Improvements in Door Arrangements for Railway Cars, of which the following is a specification.

My invention relates to new and useful improvements in door arrangements for railway cars, and more especially to the doors and locking means of hopper cars.

One of the objects of the present invention is to provide an efficient door stiffening member extending transversely of the car for securing and firmly holding a pair of doors in their proper spaced relation, the said stiffening member being provided with means which serve as seats or ledges for respectively cooperating with two supporting and locking devices mounted upon opposite sides of the car.

Another object of the invention is to provide hopper door locking mechanism advantageously applicable to cars in which the side wall or hopper sheet adjacent the discharge opening for the lading is formed with an outwardly offset portion adapted to overlap the door when the latter is closed, in which the doors themselves are fashioned with a marginal flange adapted to stand in close proximity to and be overlapped by a flange of the car side wall bordering the said offset portion.

Another and more specific object of the invention is to provide the hopper doors with a transversely extending stiffening member which is designed to extend beyond the sides of the door and to whose ends are fastened reinforcing members cooperating with door-locking members carried by the car body, the said stiffening member being reduced at its outer ends to afford clearance for flanges formed on the outer edges of the door and flanges bordering offset portions of the hopper side sheets adjacent the discharge openings of the hoppers.

A still further object of the invention is to mount a door locking member on a car body having a side sheet provided with an outwardly offset portion in such manner that said door locking member may effectively cooperate with a door hinged to the car body and adapted to extend under the said offset of the car side sheet.

With these and other objects in view the invention consists in certain new and novel arrangements and combinations of parts as will be hereinafter more fully described and pointed out in the claims.

Referring now to the drawings showing a preferred embodiment of the invention,

Fig. 1 is a view in side elevation showing a fragmentary portion of a hopper, the edge of one door and a pivotal hook locking the door in its closed position.

Fig. 2 is an end view of the construction shown in Fig. 1.

Fig. 3 is a fragmentary sectional view taken on the line 3—3 of Fig. 1.

Fig. 4 is a fragmentary sectional view taken on the line 4—4 of Fig. 1.

Fig. 5 is a fragmentary diagrammatic view of the type of hopper car to which the invention is shown as applied in the preceding figures, the dotted lines illustrating the sets of doors in their open position, and

Fig. 6 is a diagrammatic view of two hopper doors and the stiffening member extending across the same.

Referring now to the drawings more in detail, 1 indicates the side wall of a car hopper to which is securely riveted a bracket device 2 forming a housing for a movable door locking member 3, the latter preferably being formed as a pivoted hook whose jaw extends downwardly. The bracket device or housing 2 is preferably also associated with a dog or cam 4 pivotally mounted in said housing so as to be capable of being rotated into engagement with the back of the hook 3 to retain said hook in door-locking position. The dog 4 may be provided at the rear with a lug 5 affording convenient means for driving the dog to locked position and for moving it to a position allowing the hook 3 to release the door.

In the type of car illustrated in the drawings each hopper is provided with a pair of doors, as shown in Figs. 5 and 6, the open position of the doors being shown in dotted lines in the former figure. As shown in Fig. 6, the doors 7 and 8 of each pair are arranged in spaced relation on opposite sides of the center sills 6 of the car. As the pairs of doors are identical only one set will be described. In order that they may swing to open position under the influence of gravity, the doors 7 and 8 are hinged at their upper edges, as diagrammatically illustrated at 9

in Fig. 5, while they are rigidly connected so as to operate in unison by means of a stiffening member 10 which extends transversely of the car and longitudinally of the doors 5 near the free edges of the latter. The door stiffener 10, which preferably is a flanged member that may advantageously be of channel iron form, is securely riveted to the two doors 7 and 8 and preferably extends 10 outwardly beyond the far sides of the door, as indicated at 11, the ends of the stiffening member being cut away or reduced as shown at 12. Riveted to the stiffener member 10 at the ends thereof are door supporting members 13 in the form of angle irons which project outwardly beyond the adjacent sides 1 of the hopper so as to be capable of cooperating with the corresponding pivoted hooks 3 to support the doors in closed position. 15

20 The hopper side walls 1 are provided adjacent the margin of the hopper discharge opening with an outwardly offset portion 14 which is adapted to overlie the door when the latter is in closed position. Bordering 25 said offset portion on each hopper side sheet is an outwardly extending marginal flange 15 adapted to overlie a corresponding marginal flange 16 formed along the adjacent side of the door, it being understood that each 30 door is provided with such a flange 16 in proximity to the flanges 15 of the hopper side walls on opposite sides of the car. 35

Instead of terminating the flanged stiffening member 10 inside of the door flanges 16 it is preferred, as shown in Fig. 4, to notch the stiffening member by cutting away a portion of one of the flanges and a neighboring part of the web of the channel 10, thus 40 effecting a reduction in depth of the channel permitting its ends to clear the door flanges 16 and extend beyond the side walls of the car. This mode of construction effectively preserves the strength of the door structure, as it enables the marginal flange 45 17 of the channel 10 to extend continuously and uninterruptedly along the full length of the channel and especially along the portion 12 thereof which is of reduced depth; and this means of forming the ends of the stiffening members 10 so that they may clear the flanges 16 and extend beyond the hopper side sheets 1 is more advantageous than offsetting the ends of said stiffening members to clear said flanges, for, as will be apparent 50 from Fig. 5, the preferred form of construction permits the backs of the doors to come closer together when the doors are released and permitted to swing downwardly to open position. 55

60 The door supporting members 13 which overlap the ends of the stiffening member 10 are provided with a plurality of angularly disposed flanges respectively extending outwardly beyond the portions of the car body 65 on which the door locking members or hooks 3 are mounted. One of these flanges, 18, constitutes a seat for cooperating with the door locking member to support the door in locked position, while the other flange, which is secured to the web of the flanged 70 stiffening member 10 by means of rivets 19, not only forms a stiffener for said seat extending at an angle to the plane of the door, but also serves to reinforce and strengthen the overlapped portion of the member 10. 75

The flange 18 of the angle iron, besides performing its office of constituting a seat for the cooperating pivoted hook 3, provides a local marginal flange bordering the edge of the notched portion of the web of the channel 10 in parallel relation to the continuous flange 17 of the channel, which latter projects outwardly from the opposite side of the web of the channel. This construction 80 provides means for reinforcing the ends of the door stiffening member 10 in a manner affording ample strength to meet the requirements of service and at the same time produces a broad seat for cooperating with the pivoted hook 3 which will not cause undue wear either of the hook ledges 20 or the flange 18. This construction may be advantageously adopted to effect economy of material in many types of cars having different arrangements of doors. 85

As shown in Fig. 4, the rivets 19 which secure the angles 13 to the channel 10 are preferably arranged at both sides of the line of engagement of each hook 3 with the neighboring flange 18 of the angle member, 90 the majority of the rivets being located inwardly of this line of engagement. This riveting construction forms a part of the subject matter of my Patent No. 1,431,506; and said patent also comprehends certain 95 specific applications of the broad features of invention herein described and claimed. 100

When in door locking relation the pivoted hooks 3 lie in substantially horizontal positions. They are adapted to swing upwardly and downwardly for engagement with or disengagement from the respective cooperating flanges 18 of the door supporting members 13, the door engaging ledges 20 being formed on the lower edges of the hooks 105 at points somewhat removed from the outermost ends 21 of the latter. The portion 22 of the lower edge of each hook is formed as an approach portion adapted to cooperate with the neighboring flange 18, so that when the doors are swung to closed position the contact of the said flange 18 with the approach portions of the hooks will cause said hooks to swing upwardly, thereby permitting them to ride over the outermost edges of the flanges 18. The hooks will then fall by gravity so that the corresponding ledges 20 thereof come 110 into engagement with the corresponding flanges 18. 115

120

125

130

The bracket device or housing 2 for the pivoted door locking hook 3 is secured to the hopper side wall 1 back of the offset portion 14 of said wall and is preferably made in two parts, the outer portion being spaced from the hopper side wall and overlying the pivoted hook 3 with which it is associated, and the inner portion constituting means for maintaining the door locking member 3 in spaced relation to the side wall 1 of the hopper permitting it to swing in a plane passing outside of the flange 15 bordering the offset portion of said hopper side wall. In order that the hooks 3 may not drop by gravity into positions where their approach portions 22 would not cooperate with the flanges 18 of the corresponding door supporting members when the doors are forced shut, the outer or housing portion of each bracket 2 is provided with an offset at 23 serving as a stop for limiting the fall of the hook when the doors are open.

The operation of the doors is exceedingly simple. The closing of the doors is most conveniently effected by two men working together. Each man may grasp one of the outwardly projecting angles or door supporting members 13 and swing the doors upwardly in unison, the said doors being connected by the stiffening member 10. When the doors have reached their closed position, the pivoted hooks 3 will drop by gravity and engage the correspondingly adjacent flanges 18 of the angle members 13, thus maintaining the doors in closed position. The dogs 4 may then be rotated so as to jam them against the rear of the hooks 3, thereby making it impossible for the doors to open accidentally.

To open the doors the operation is reversed. The lugs 5 on the locking dogs 4 provide convenient surfaces or projections which may be hit with a hammer to effect a releasing rotation of said dogs. After this is accomplished the hooks 3 may be forced upwardly and the doors thus be allowed to swing to their open position.

From the foregoing, it will be seen that I have provided an arrangement whereby two hopper doors may be moved in unison and will always be rigidly held in their spaced relation, the means accomplishing this function also forming ledges which are engaged by the locking devices secured to the sides of the hopper. Furthermore, a relatively tight fit is provided between the outer edges of the hopper and the hopper doors. The entire construction is one that is relatively cheap, easily applicable to the hopper cars, and extremely efficient.

Many slight changes may be made without in any way departing from the spirit and scope of the invention.

What I claim is:

1. In a door arrangement for railway

cars, a door hinged to the car body and having one edge lying along the car side, a stiffening member secured to the outer face of the door, the same having a web outstanding from the door and having a marginal flange extending continuously and uninterruptedly along one edge of the web, the said stiffening member having an end projecting outwardly beyond the edge of the door and beneath the side of the car, the said projecting end being of reduced depth compared to that of the major portion of said member and said reduction in depth being effected along the edge of the member opposite to that carrying the said marginal flange, a local marginal flange secured along the edge of the projecting end of the stiffening member and arranged to lie substantially parallel with the said continuous marginal flange and bordering the edge of the web opposite that carrying said continuous flange, and a door supporting hook pivoted to the side of the car and arranged to seat beneath the said local marginal flange.

2. In a door arrangement for railway cars, a door hinged to the car body and having one edge lying along the car side, a flanged stiffening member secured to the outer face of the door with one end thereof extending beyond the line of the car side, a flange portion of the stiffening member being cut away near the outer end thereof and a flanged reinforcing member being secured to the stiffening member at the said reduced portion thereof, the flange of the reinforcing member lying in a different plane from the flange of the stiffening member, and door-securing means operatively interposed between the car side and the flange of the said reinforcing member.

3. In a door arrangement for railway cars, a door hinged to the car body and having an out-turned flange formed along one of its edges, a stiffening member secured to the outer face of the door and extending over the flanged edge of the same, the said stiffening member being notched to clear the said flange, a reinforcing member secured to the stiffening member at the said notched portion thereof, and door securing mechanism carried by the car and adapted to cooperate with said reinforcing member.

4. In a door arrangement for railway cars, a door hinged to the car body and having one edge lying along the car side, a door-supporting hook pivoted to the car side adjacent the said edge of the door, and a stiffening member secured to the outer face of the door provided with an end projecting outwardly beyond the said edge of the door and beyond the line of the car side, the said stiffening member having for substantially its full length a continuous marginal flange extending uninterruptedly along the said

1. projecting end thereof, and the edge of the projecting end of the said stiffening member opposite said flange being of reduced depth as compared to that of the main portion of the stiffening member and being provided with a local marginal flange in the vicinity of and adapted for engagement by the said door-supporting hook.
2. In a door arrangement for railway cars, a pair of doors hinged side by side to the car body and extending transversely of the same, a stiffening member secured to and connecting both doors to maintain them in spaced relationship, said stiffening member being formed of a channel-shaped section extending transversely of the car and longitudinally of the doors near their free edges and having one of its flanges contacting the door, the said stiffening member being of greater length than the width of the car body and having its ends extending beyond the lines of the car sides, the door-contacting flange of the channel being cut away near the ends thereof to form portions of reduced depth, and reinforcing angle irons being secured to the channel at the said reduced portions thereof, and door-securing means operatively interposed between the respective car sides and the said reinforcing angles.
3. In a door arrangement for railway cars, a pair of doors hinged side by side to the car body and extending transversely of the same, a channel member secured to and connecting both doors, said channel member extending transversely of the car and longitudinally of the doors, near their free edges, and being arranged to hold the two doors in a definite spaced relationship and being of greater length than the width of the car body and having its ends extending beyond the lines of the car sides, door-securing means attached to the car sides adjacent to the ends of the channel member, and reinforcing angles attached to the ends of the channel member, the said angles being arranged for co-operation with the said door-securing members.
4. In a door arrangement for railway cars, a pair of doors hinged side by side to the car body and extending transversely of the same, a stiffening member secured to and connecting both doors and extending transversely of the car and longitudinally of the doors near their free edges, said stiffening member being arranged to hold the two doors in a definite spaced relationship and being of greater length than the width of the car body and having its ends extending beyond the lines of the car sides, door-securing means attached to the car sides adjacent the ends of the stiffening member, and reinforcing members attached to the ends of the stiffening member, the said reinforcing members being arranged for co-operation with the said door-securing means.
5. A railway car having a hopper with a discharge opening and a door for said opening, the said hopper including a side sheet which is outwardly offset near said discharge opening, door-securing means carried upon the outer face of the side of the hopper and including a bracket secured to the hopper side, a door-locking member movably mounted upon the bracket and overlying the offset portion of the hopper side sheet, the said bracket being disposed back of the offset portion of the hopper side sheet and arranged with its outer portion spaced from the hopper side in such manner as to allow the free operation of the said door-locking member along the edge of the said offset portion of the hopper side, and means carried by said door for cooperating with said door-locking member to support said door.
6. A railway car having a hopper with a discharge opening and a door for said opening, said hopper being formed with a side wall which adjacent the margin of said discharge opening is provided with an outwardly offset portion adapted to overlap said door when the latter is in closed position, door-securing means carried upon the outer face of said hopper side wall including a bracket and a door-locking member movably connected to said bracket and overlying said offset portion of said hopper side wall, said bracket being secured to said hopper side wall back of the said offset portion and having its outer portion spaced from said hopper side wall and overlying said door-locking member, and means carried by said door projecting outwardly beyond said offset portion of the hopper side wall adapted to cooperate with said door-locking member to support said door.
7. A railway car having a hopper with a discharge opening and a hinged door for said opening, said door being provided with an outwardly extending marginal flange, said hopper being formed with a side wall having an outwardly offset portion adapted to overlap said door when the latter is in closed position and having a flange bordering said offset portion and adapted to overlie the said marginal flange of said door, a transversely extending flanged stiffening member secured to the outer face of said door adjacent the free edge thereof, door-securing means carried upon the outer face of said hopper side wall including a bracket device secured to said side wall back of the offset portion thereof and a door-locking member pivotally connected to said bracket device back of said offset, said bracket device having a portion spaced from said hopper side wall and overlying said door-locking member and also having means

- for maintaining said door-locking member in spaced relation to said side wall so as to allow it to swing in a plane passing outside of the flange bordering the offset portion of said hopper side wall, and a door-supporting member mounted upon said door for co-operating with said door-locking member to support said door, said door-supporting member being rigidly secured to 10 said stiffening member and extending under the said marginal flange of the door and under the said bordering flange of the offset portion of said hopper side wall and projecting outwardly beyond said last named 15 flange, and said door-supporting member being formed as a flanged member having one portion thereof forming a seat for said door-locking member and having another portion disposed in a plane at an 20 angle to said seat and to the plane of said door.
11. A railway dump car having a discharge opening and a hinged door for said opening, said door being adapted to swing open under the influence of gravity, a flanged stiffening member secured to the outer face of said door adjacent the free edge thereof, door-locking means movably mounted on the car adjacent said discharge 25 opening and projecting outwardly beyond the inner face of the door when said door is in closed position, and a door-supporting member mounted upon said door and adapted for engagement by said door-locking means to support said door, said door supporting member being rigidly secured to 30 said stiffening member and being provided with a plurality of angularly disposed flanges overlapping said stiffening member and extending outwardly beyond the portion of the car on which said door-locking member is mounted, one of said angularly disposed flanges being spaced outwardly 35 from said door and constituting a seat for 40 cooperating with said door-locking member, and the other of said flanges forming a stiffener for said seat disposed at an angle to the plane of the door.
12. A railway dump car having a discharge opening and a door for said opening, said door being hinged to the car body so as to swing open under the influence of gravity, a door-locking member movably mounted upon the car body adjacent said discharge opening and projecting outwardly 45 beyond the inner face of the door when said door is in closed position, a stiffening member secured to the outer face of said door adjacent the free edge thereof, and a flanged member overlappingly secured to the end of 50 said stiffening member and extending outwardly beyond the portion of the car body on which said door-locking member is mounted in position to be supportingly engaged by said door-locking member when 55 said door is in closed position, said door-supporting member having a plurality of flanges extending at an angle to each other, one of said flanges forming a seat for cooperating with said door-locking member and the 60 other of said flanges overlapping said stiffener member and forming a stiffener for said seat extending at an angle to the plane of said door.
13. A railway car having a hopper with a discharge opening and a hinged door for said opening, said hopper being formed with a side wall having an outwardly offset portion adapted to overlap said door and having a flange bordering said offset portion in position to project outwardly beyond the inner face of said door when said door is in closed position, a movable door-locking member overlying said flange and projecting beyond the same, and means secured 65 to the outer side of said door cooperating with said door-locking member to support said door.

In testimony whereof I affix my signature.

WILLIAM E. WINE.

DISCLAIMER

1,486,210.—*William E. Wine*, Toledo, Ohio. DOOR ARRANGEMENT FOR RAILWAY CARS. Patent dated March 11, 1924. Disclaimer filed August 22, 1935, by the assignee, *Wine Railway Appliance Company*.

Hereby enters this disclaimer to that part of the thing patented which is claimed in said patent in the following words, to wit:

“1. In a door arrangement for railway cars, a door hinged to the car body and having one edge lying along the car side, a stiffening member secured to the outer face of the door, the same having a web outstanding from the door and having a marginal flange extending continuously and uninterruptedly along one edge of the web, the said stiffening member having an end projecting outwardly beyond the edge of the door and beneath the side of the car, the said projecting end being of reduced depth compared to that of the major portion of said member and said reduction in depth being effected along the edge of the member opposite to that carrying the said marginal flange, a local marginal flange secured along the edge of the projecting end of the stiffening member and arranged to lie substantially parallel with the said continuous marginal flange and bordering the edge of the web opposite that carrying said continuous flange, and a door supporting hook pivoted to the side of the car and arranged to seat beneath the said local marginal flange.”

“4. In a door arrangement for railway cars, a door hinged to the car body and having one edge lying along the car side, a door-supporting hook pivoted to the car side adjacent the said edge of the door, and a stiffening member secured to the outer face of the door provided with an end projecting outwardly beyond the said edge of the door and beyond the line of the car side, the said stiffening member having for substantially its full length a continuous marginal flange extending uninterruptedly along the said projecting end thereof, and the edge of the projecting end of the said stiffening member opposite said flange being of reduced depth as compared to that of the main portion of the stiffening member and being provided with a local marginal flange in the vicinity of and adapted for engagement by the said door-supporting hook.”

[*Official Gazette September 10, 1935.*]
